RECTIFIER

William M. Fury, Philadelphia, Pa.

Application March 18, 1933, Serial No. 661,438

5 Claims. (Cl. 250—27.5)

My invention relates to new and useful improvements in rectifier types of vacuum tubes, so constructed and of such materials so as to afford a time delay in the operating efficiency of same as a rectifier, in such manner as to eliminate the excessive peak voltages, so named because they are in excess of the normal operating requirements of the associated devices, and common to the operation of present day types of rectifier tubes, of the direct heater types, principally used in radio receiving and broadcasting devices, recording devices, light sensitive devices, and "talkies", and any other devices which require direct current potentials and depend on a 15 rectified alternating current supply.

An object of the invention is decreased cost in manufacture of associated devices, because of the fact that the unnecessary and excessive peak voltages are eliminated by this invention, thereby 20 permitting associated devices with a lower safe voltage rating than that of present requirements.

A further object of the invention is to decrease the cost in transportation of associated devices, 25 because of the fact of the permissible lower voltage rating of the associated devices as heretofore stated, the associated devices shall comprise less bulk.

A further object of the invention is to decrease the cost in maintenance of associated devices, because of the fact that not only the excessive peak voltages are eliminated by this invention, but particularly due to the fact that this invention, 30 instead of delivering voltages in excess of the normal requirements and instantaneous, as of present day direct heater types of rectifier, this invention delivers voltages gradually, that is, from zero volts to maximum, the latter of which is 35 to be so proportioned in manufacture and the type of materials used therein, that it will not be in excess of the normal operating requirements of the associated devices, considering the said associated devices to be electrically perfect and so 40 assembled as to conform with the theoretical operation of this invention, such as is necessary in present types of rectifier tubes.

A further object of the invention is the structure providing time delay, that is, from start 45 or zero volts (rectified), to maximum volts which shall be so proportioned in manufacture as heretofore stated, as to conform with the time delay in the associated devices' absorption of current, that is, from start to the time delay necessary before the associated devices actually absorb 50

their full amount of current, the time delay of the invention preferably being slightly in excess of that of the associated devices.

A further object of the invention is a structure to supply voltages to associated devices gradually, 5 as heretofore stated, regardless of whether the associated devices comprise parts or devices which require a given time before they absorb their full amount of current, the former of which is much less abrupt and hazardous than supplying 10 the voltages instantaneously in the full amount or in excess of the requirements as of present day types of rectifier tubes.

I have accomplished the said objects by so designing and constructing rectifier types of vacuum tubes, which would function or deliver rectifier voltages and currents in a smooth but gradual manner, that is, from zero volts at start and gradually increasing in a time ratio as heretofore explained, to the full value of voltages and currents, and to not exceed that value, by the incorporation of indirect heaters or cathodes in rectifier types of vacuum tubes, the action and connections of which is herein further explained. 15 20 25

The drawings illustrate an embodiment of the invention and the views therein are as follows:

Figure 1 is a view showing a tube broken away, containing the structure of the present invention shown in side elevation, with parts broken away 30 to show the internal construction,

Figure 2 is a view of the internal construction in edge elevation, as indicated by arrow 2 at Figure 1, and also exhibiting arrow 1 as the direction from which Figure 1 is taken, 35

Figure 3 is a transverse sectional view through the operating parts, taken on line 3—3 of Figure 1,

Figure 4 is a top plan view of the operating structure, as indicated by arrow 4 at Figure 1, 40

Figure 5 is a detail perspective view of the plate with the bendable ear by which the device is assembled, and

Figure 6 is a fragmentary perspective view in 45 an enlarged detail, showing the upper end of the cathode insulator and sleeve, parts being broken away to show the construction more completely.

Figure 7 is a diagrammatic view of the rectifier, exactly as shown at Figures 1 to 5 inclusive, 50

Figure 8 is a diagrammatic view similar to Figure 7, except that the cathode is connected to an independent conductor,

Figure 9 is a diagrammatic view similar to Figure 7, except that the cathodes associated with 55

each plate are connected together and to independent conductors.

Like characters of reference indicate corresponding parts throughout the several views.

5 The present invention, being of the tube type of rectifier, comprises, naturally, a tube 10 and base 11 of substantially the usual and ordinary type. Within the tube is mounted a flare 12 to which the operating structure is attached and 10 upon which it is supported, prior to its introduction into the tube 10 and the evacuation of the tube in the usual well-known manner.

15 The structure carried by the flare 12 comprises supporting conductors 13 and 14 which are molded into the material of the flare in the usual manner, bosses 15 and 16 being shown, but employed only as, if and when the structure otherwise makes them desirable.

20 Upon the supports 13 and 14 an insulating plate 17 is employed, having perforations therethrough to receive the structure hereinafter enumerated. This plate 17 may be of any insulating material, but preferably of mica.

25 Upon the supports 13 and 14 are mounted plates or anodes 18 and 19. These plates are, of course, of metal, as is well-known in the art, and are secured to the supports by being distorted at 20 and 21, as indicated more particularly at Figures 1 and 3, so that the supports 13 and 14 are clamped fixedly between the offsets 22 and 23 of the plates.

30 Upon the top of the plates 18 and 19 a second insulating plate 24 is mounted. The plates 18 and 19 are provided each with a pair of ears 25 at the top, and similar ears 26 at the bottom, 35 which are inserted through openings 27 in the top plate 24 and openings 28 in the bottom plate 17, and are bent over, as shown more particularly at Figures 2 and 4, and in dotted lines at Figure 5, so that the plates 17 and 24 are spaced permanently apart by the intervening plates 18 and 19.

35 Within the plates 18 and 19 insulators are positioned. These insulators comprise elongated multi-tubular members 29, which have passages therethrough with hair-pin shaped filaments 30 extending through parallel passages in the insulating tubular structures 29.

40 Means is provided for properly positioning these insulators between the plates 17 and 24. Preferably, this means is also the metal sleeve 31 providing an indirect heater which closely embraces the insulator 29 and provides shoulders which bear against the approximate sides of the plates 17 and 24.

45 The insulators 29 themselves pass through the plates, and at opposite ends are provided with wings 32 which fit in perforations of similar form in said plates, and bear against the opposite ends of the embracing sleeves 31.

50 Sealed also into the flare 12 are conductors 33 and 34 which are bent in opposite directions, as shown more particularly at Figure 2, and provided, respectively, with bars 35 and 36.

55 The extended ends of the filaments of one pair, as indicated at 30' in Figure 2, are crossed and connected, while the opposite ends of said filaments, 30'', are respectively secured to the bars 35 and 36.

60 The sleeves 31 are also provided with tongues 37 and 38, which are respectively secured to the bars 35 and 36.

65 The structure may also be provided with a getter plate or a getter cup 39, and mercury cup 40, 70 which are employed, respectively, for completing

the evacuation and reducing the internal resistance in the usual well-known manner.

75 The several conductors 13, 14, 33 and 34, are, of course, continued outwardly through the flare 12 and connected with the usual pins in the base 11 (not shown), to conform with standards already established, or which may hereafter be established.

80 The drawings are but one type of rectifier, of the vacuum tube type, to which this invention is applicable, and is so shown and described merely to illustrate and describe the application of this invention in rectifier types of vacuum tubes, and it is to be understood that this invention shall not be limited to that particular type of rectifier type construction.

85 One form of this invention is illustrated in the drawings, in which each cathode sleeve is electrically connected by its associated tongue, to its associated filament conductor. Instead of interconnecting said pair of cathode sleeves, as shown in Figures 1 to 6 inclusive and above described, the cathode sleeves 31, associated with and encircled by plate 18, may be electrically connected to each other, and be electrically connected to an independent conductor 41—Figures 12 to 16 inclusive, the latter of which is to protrude from the flare as other conductors, for electrical connection to an additional and independent base pin. The other pair of cathode sleeves 31 associated with an encircled by plate 19, may be similarly connected by an additional conductor 42 similarly mounted in the flare, or all cathodes within the envelope may be electrically connected together and to an independent conductor 41, 35 as shown in Figures 17 to 20 inclusive. Regardless of the manner in which the cathode sleeves and/or filaments are interconnected, the principles of this invention remain the same.

90 As the operation of rectifiers, in general, and especially of the tube type, are so well-known, it is believed that a further description of the operation of the device would be superfluous.

95 Of course, the rectifier herein illustrated may be modified and changed in various ways without departing from the invention herein set forth and hereafter claimed.

I claim:—

1. A tube type rectifier comprising a plate bent to form a hollow chamber, a pair of cathodes mounted within the chamber and spaced apart, said cathodes comprising metallic sleeves filled by insulating material having longitudinal passages therethrough, filaments extending through one of each of said passages and bent back upon itself and extended beyond the same end of said insulator, one of said extended ends being connected with an extended end of the other of said filaments, the other ends of said filaments being electrically connected with the sleeves, and conductors leading into said tube and connected with said opposite ends of the filaments.

2. A rectifier comprising an anode of tubular conductive material, a plurality of indirectly heated cathodes mounted within and spaced from the anode, heating elements mounted within and insulated from the cathodes, insulating means supporting and structurally connecting the foregoing into a unit, an evacuated envelope enclosing said unit, separate conductors from the heating elements and anode passing through the envelope, and means within the envelope connecting the cathodes to a conductor from a heating element.

3. A rectifier comprising a plurality of anodes

of tubular conductive material, a plurality of cathodes of tubular conductive material mounted within and spaced from each anode, a heating element mounted within and insulated from each cathode, insulating means supporting and structurally connecting the foregoing into a unit, an evacuated envelope enclosing said unit, conductors from the heating elements and each anode passing through the envelope, and means within the envelope connecting an equal number of cathodes to each conductor from the heating elements.

4. A rectifier comprising a plurality of anodes of tubular conductive material, a plurality of cathodes of tubular conductive material mounted within and spaced from each anode, a heating element mounted within and insulated from each cathode, insulating means supporting and

structurally connecting the foregoing into a unit, an evacuated envelope enclosing the unit, and conductors from the heating elements from each anode and from each group of cathodes within an anode separately passing through the envelope.

5. A rectifier comprising a plurality of anodes of tubular conductive material, a plurality of indirectly heated cathodes of tubular conductive material mounted within and spaced from each anode, a heating element mounted within and insulated from each cathode, means supporting, insulating and connecting the foregoing into a unit, an evacuated envelope enclosing the unit, and conductors passing through the envelope, separately for the cathodes, for each anode and for the heating elements.

WILLIAM M. FURY.
